[57] **CLAIM**

The ornamental design for a jar, as shown and described.

DESCRIPTION

FIG. 1 is a front elevational view of a jar showing my new design;

FIG. 2 is a side elevational view thereof; and

FIG. 3 is a top plan view thereof.

The side opposite that shown in FIG. 1 is the same in appearance as the side shown.

FIG. 1

FIG. 2

FIG. 3
